RAY H. MANSON, OF ELYRIA, OHIO, ASSIGNOR TO THE GARFORD MANUFACTURING COMPANY, OF ELYRIA, OHIO, A CORPORATION OF OHIO.

AUTOMOBILE OR MOTOR-CYCLE HORN.

1,183,576.

Specification of Letters Patent. Patented May 16, 1916.

Application filed May 4, 1914. Serial No. 836,153.

To all whom it may concern:

Be it known that I, RAY H. MANSON, a citizen of the United States, residing at Elyria, in the county of Lorain and State of Ohio, have invented certain new and useful Improvements in Automobile or Motor-Cycle Horns; and I do hereby declare the following to be a full, clear, and exact description of the invention, such as will enable others skilled in the art to which it appertains to make and use the same.

This invention relates to signaling devices, such as are employed upon automobiles or motor cycles to give a warning signal of the approach of the vehicle, and while designed especially for this use, it is obviously adapted for other uses.

One of the particular objects of my invention is to produce a horn of such construction that the necessity of adjusting for wear or deformity between the sound producing parts resulting from use is eliminated. I also aim to produce a horn in which the allowance for this wear is automatically taken up by the horn.

Another particular object of my invention is to increase the efficiency of the magnet circuit, and thereby increase the loudness and intensity of the sound produced by the horn.

Other particular objects of my invention are to increase the efficiency of the horn, to produce a cheaper horn, and one which can be more easily and conveniently made by standard tools and standard processes and one which will operate to produce a loud noise upon a comparatively small amount of current.

Still other objects of my invention and the invention itself will probably be better understood from a description of a particular embodiment of the invention.

Figure 1 is a plan view of an embodiment of my invention with the rear cover removed. Fig. 2 is a section through the embodiment of my invention illustrated in Fig. 1. Fig. 3 is a detail showing the electric contacts.

Referring now to the drawings and to the particular embodiment illustrated therein, it is shown the casing front, perforated at 5 for the egress of sound waves produced by the horn. A resonator may be mounted in this opening, as illustrated at 6. Suitable

means are provided for connecting the resonator to the casing front. In the form shown, the edges of the front 4 around the opening 5 are turned up to form an annular collar member 7, and the small end of the resonator is crimped as shown at 8, the crimp 8 embracing the collar 7 and holding the resonator and front firmly together. The casing front is struck outward, as shown at 9, to form a chamber in front of the diaphragm 10, within which the diaphragm vibrates. Suitable sound producing means, such as the diaphragm 10, is provided mounted as shown in the front 4, or in any other suitable manner. A gasket 11 of any suitable material, such as linen, cork or rubber 70 may be placed between the diaphragm and the casing front. The outer edges 12 of the casing front 4 are turned backward like the walls of a cup to form a receptacle for the diaphragm and frame piece.

At 13 I show a frame piece behind the diaphragm. This frame piece is of suitable width, being preferably made as thin as possible, and is provided with an opening 14, here shown as a large opening, through 80 which the diaphragm is exposed at the rear. The means for actuating the diaphragm, consisting of electromagnetic means, is mounted upon the frame piece. At 15 is shown an electromagnet consisting of a core 85 16 and a winding 21. Any suitably shaped core may be employed, though I realize special advantages from the use of an E-shaped core, such as is shown in the embodiment illustrated. One method of increasing 90 the efficiency consists in building the core of laminations, which may be punchings, preferably machine punchings. In the form shown, the middle arm 18 is made shorter than the arms 19 and 20 for a purpose to be 95 described.

The electromagnet is preferably so mounted that a portion thereof, as shown in the drawing, a portion of the winding, is below the rear surface of the frame-piece and in 100 the opening in the frame-piece. By this means I may make the device still more compact.

The magnet winding, which I prefer to make into one coil, is mounted upon the 105 middle limb. Suitable means, such as screws 25, are employed for connecting the electromagnet to the frame piece, and when

mounted thereon, the core and winding are substantially parallel to the diaphragm, thus making the device very compact. The screws 25 pass through each of the punchings fastening the core to the frame-piece, with the arms thereof substantially equidistant from the diaphragm. The armature is shown at 30 and may be built of a plurality of laminations 31. This, however, I do not claim as part of my invention, as it is old to form armatures of laminations. These laminations are mounted upon a member 31, which is connected by suitable means, such as screws 32, to a leaf spring 33, the other end 34 of which is connected by any suitable means, such as a screw or rivet 35, to the frame piece 13. The member 31 carries a hammer 40 for striking the diaphragm when the armature is vibrated. I prefer to form the member 40 integral with the member 31, and this is best accomplished as illustrated in the drawing by forming a tongue in the central part of the member 31, the end parts 50 of the member 31 being employed to support the armature. The armature 30 is mounted to one side of the magnet, but closely adjacent thereto, where it may be conveniently and efficiently operated by said magnet. When thus operated, the armature swings to one side of said magnet structure in a path which clears the magnet. I prefer to mount the armature in front of the magnet structure, as illustrated in the embodiment shown. These parts are best so mounted that were they projected upon the plane of the diaphragm such projections would not overlap or interfere. For this reason, these parts may be mounted close to the diaphragm, thereby economizing much space.

No parts of the electromagnet are in the path of travel of the armature, so that the armature will always move clear of the magnet, no matter how great or small the arc of its travel. This is of especial advantage, because in case the diaphragm buckles or the member 40 is worn, dented or turned up, there will be no necessity for adjusting the horn. The only result will be a slight change in the length of the arc traveled by the armature.

At 60 is shown an electric switch consisting of two contacts 61 and 62, each mounted upon a spring, the contact 61 being mounted upon the spring 63 and the contact 62 upon a spring 64. These springs are mounted through suitable means, such as insulating members, screws, bolts, etc., all of which constitute no part of my invention, to a supporting bracket 70. The supporting bracket 70 is provided with an arm 71, projecting substantially at right angles thereto, to which the contact springs are directly connected. The bracket 70 is connected to the frame piece, preferably by the

same means as the spring 33 is connected thereto, the bracket 70 being bent upward at 74 and over at 75, so that the arm member 70 is substantially parallel to the armature.

I provide suitable means 80 for adjusting the contact 61. A pair of terminals 81 and 82 are mounted upon the frame piece 13. A conductor 90 leads from the terminal 81 to one terminal of the magnet winding 15. Conductors 92 and 93 connect the other terminal through the switch 60 to the other winding of the electromagnet. The front, the frame piece and the diaphragm are connected by suitable means, such as screws or bolts, 100. The whole may be inclosed by a rear casing 101.

The contacts 61 and 62 are controlled in any suitable way by the armature. In the embodiment shown, the spring 64 is normally stressed to open these contacts, but is prevented from doing so by the spring 33. When, however, the armature is attracted, the upward pressure normally exerted upon the spring 64 by the spring 33 is relieved and the contacts 61 and 62 separated. Suitable electric conductors, source of current and current controller may be connected to these binding posts. All of this is well understood and constitutes no part of my invention.

When operated, the armature moves in a path which is unobstructed, except by the hammer striking the diaphragm. The E-shaped cores and the armature swinging between the end limbs thereof, results in a very efficient magnetic circuit and a very loud noise is, therefore, produced.

As will be seen, the lines of magnetic force extend through a considerable air gap from the end of the limb 18 to the armature 30. The return magnetic circuit is through the ends of the armature and the comparatively short air gap to the return pole pieces of the other limbs. When the armature is energized, this action causes the armature to be drawn down, thereby reducing the air gap so that when the projection 40 strikes the diaphragm, the air gap is sufficiently reduced, so that the magnetic force is increased to a high point and thereby a very strong blow is struck on the diaphragm. In this action the return path through the ends of the armatures to the side members of the magnet core does not vary materially.

The parts employed are easily and cheaply made, the apparatus consisting almost entirely of machine punchings of such shape as to be made by a minimum number of operations.

I have shown this embodiment of my invention to illustrate the invention and not that I wish to be limited to the form and details of this embodiment, which admits of many variations without departing from the

spirit of the invention, which is more particularly set forth in the appended claims.

I claim:

1. In an automobile or motorcycle horn, the combination of a flat frame piece having an opening in the central portion thereof and provided with an inclined switch support inclined upwardly toward the center of the support, a pair of contact carrying members comprising an electric switch and means to connect said members to said support, a vibratile sonorous diaphragm and means to connect said diaphragm to the front side of the frame piece, including a plurality of screws and a casing front provided with an opening for the egress of sound waves initiated by the diaphragm, an armature controlling said switch connected on the back side of the framepiece, means controlled by said armature adapted to be operated through the opening in the frame piece to cause the actuation of the diaphragm, an electromagnet for actuating said armature and means to connect one end 25 of the magnet to the back side of the frame piece adjacent the periphery of the frame piece, the magnet being held in position substantially parallel to the diaphragm with its other end free and adjacent the center of 30 the diaphragm.

2. In an automobile horn, the combination of a frame piece, a diaphragm associated therewith, an electromagnet supported from the frame substantially parallel to the diaphragm and with its operating end adjacent the central portion of the diaphragm, an armature controlled by the electromagnet for actuating the diaphragm, said armature when attracted by the electromagnet moving 40 substantially perpendicularly to the long axis of the magnet, means supported from the frame for supporting and positioning the armature to move in a path clearing in the front of the electromagnet and an electric switch controlled by the armature.

3. In an automobile or motorcycle horn, the combination of a frame, a diaphragm associated therewith, an electromagnet supported from the frame piece including an 50 E-shaped core and a winding on the limb of the core, an armature adapted when attracted to move in a path clearing the front of the magnet to cause the actuation of the diaphragm and means to connect the armature 55 to the frame piece.

4. In an automobile or motorcycle horn, the combination of a flat frame piece, a diaphragm connected to the front side thereof, a magnet including an E-shaped core, means 60 to connect the vertical or interconnecting limb of the E-shaped core to the frame piece adjacent the periphery thereof, said magnet when so connected extending substantially parallel to the diaphragm with its other end 65 free and adjacent the central portion of the

diaphragm, an armature adjacent the free end of said magnet adapted to be operated by said magnet to cause the actuation of the diaphragm, spring means for returning the armature to normal and means to connect 70 said armature and spring means to the frame piece.

5. In an automobile horn, the combination of a frame, a diaphragm associated therewith, an electromagnet supported from 75 the frame including an E-shaped core, the end limbs extending beyond the middle limb, a winding on the middle limb, an armature controlling the operation of the diaphragm adapted when attracted to swing between 80 the extended ends of the end limbs of the core and a spring supported from the frame upon which the armature is mounted.

6. In an automobile horn, the combination of a casing front, a flat frame piece having 85 a large opening in the center thereof, a diaphragm clamped between the front and frame piece, an electromagnet comprising an E-shaped core built of laminations, the end limbs of the core extending beyond the 90 central limb, means for connecting one end of the core to the flat frame piece, a coil on the central limb of the core, said core and coil being substantially parallel to the diaphragm when mounted in position on 95 the frame piece, an armature for the electromagnet controlling the actuation of the diaphragm, said armature when in attracted position being between the extended portions of the end limbs of the core and in 100 front of the central limb, a spring connected at one end to the frame piece and at the other to the armature, and an electric switch controlled by the armature.

7. In an automobile horn, the combination of a casing front, a flat frame piece having a large opening therein, a diaphragm and means to connect the diaphragm, casing front and frame piece together, an electromagnet comprising an E-shaped core, the 105 central limb of which is shorter than the two end limbs, said core being constructed of a plurality of punchings, means to connect the closed end of the core to the rear of the flat frame piece with the core substantially parallel to the diaphragm, a magnet coil mounted on the short limb, a spring member supported at one end from the frame piece, an armature mounted on the free end of the spring member and normally 110 held behind the central portion of the core and between the extended portions of the end limbs of the core, said armature when vibrated swinging between the extensions 115 of the end limbs and in front of the short limb of the core, means carried by the armature for actuating the diaphragm and an electric switch controlled by the electromagnet.

8. In an automobile horn, the combination 120

- of a frame, a diaphragm associated therewith, an electromagnet, a spring supported from the frame piece, an armature connected to the free end of the spring and normally held in position behind the central portion of the core of the electromagnet, said armature when attracted swinging in a path which clears the free end of the core and approaching the diaphragm to cause the same to be actuated, and a switch controlled by the electromagnet.
9. In an automobile horn, the combination of a frame, a diaphragm associated therewith, an electromagnet associated therewith, a bracket supported from the frame piece, an arm on the bracket, a plurality of contact springs connected to the end of the arm and extending under the bracket, contacts on the ends of the springs under the bracket and an armature controlled by the electromagnet governing the switch contacts.
10. In an automobile horn, the combination of a frame, a diaphragm associated therewith, an electromagnet associated therewith, a bracket supported from the frame piece at one end and bent upward and outward, an arm on the end of the bracket, a pair of contact springs connected to the end of the arm and extending under the bracket, contacts on the ends of the contact springs under the bracket and an armature actuated by the electromagnet controlling the contacts.
11. In an automobile horn, the combination of a casing front having an opening therein for the egress of sound waves, a flat frame piece having a large opening in the central portion thereof, a diaphragm and means to connect the casing front, diaphragm and frame piece together, an electromagnet comprising an E-shaped core having a short central limb and a magnet winding on said central limb, means to connect the core at its closed end to the back side of the flat frame piece, said magnet when connected to the frame piece extending over the opening in the frame piece and being held in position substantially parallel to the diaphragm, a flat leaf spring connected at one end to the flat frame piece and extending over the opening in said frame piece, an armature on the free end of the spring adapted when attracted to swing between the extended portions of the end limbs of the core and in front of the central limb thereof, a hammer controlled by the armature for actuating the diaphragm, a bracket supported from the frame piece bent upward and outward, an arm on the bracket and a plurality of contact springs connected to the arm and carrying contacts controlled by the armature.
12. In an automobile horn, the combination of a frame, a diaphragm supported from the frame and substantially parallel to the diaphragm and with its operating end adjacent the central portion of the diaphragm, said magnet extending part way over the diaphragm, an armature for the magnet, means supported from the frame for supporting and positioning the armature in front of the electromagnet and over the central portion of the diaphragm, said armature when attracted by the magnet swinging in front of the magnet in a path which clears the magnet and substantially perpendicular to the long axis of the magnet, and an electric switch controlled by the armature.
13. In an automobile horn, the combination of a flat frame piece having a large opening in the center thereof, a diaphragm associated with the frame piece and in front thereof, an electromagnet mounted upon the back side of the frame piece and extending part way across the opening in the frame piece substantially parallel to the diaphragm, an armature for said magnet and means including a spring supported from the flat frame piece for positioning and normally holding the armature in front of the magnet and over the central portion of the diaphragm, said armature when attracted by the magnet swinging in front thereof in a path which clears the magnet and in a direction substantially perpendicular to the long axis of the magnet, and a switch controlled by the armature.
14. In an automobile horn, the combination of a flat frame-piece having a large opening in the center thereof, a diaphragm associated with the frame-piece and in front thereof, means to connect the diaphragm to the frame piece, an electromagnet mounted upon the backside of the frame-piece and extending part way across the opening in the frame-piece substantially parallel to the diaphragm, means to connect the magnet to the frame-piece holding it normally with its operating end adjacent the central portion of the diaphragm, a portion of said magnet being in the opening in the frame-piece between the diaphragm and the rear surface of the frame-piece, an armature for said magnet and means including a spring supported from the frame-piece for positioning and normally holding the armature to one side of the magnet and over the central portion of the diaphragm, said armature when attracted by the magnet swinging to one side thereof in a path which clears the magnet and in a direction substantially perpendicular to the long axis of the magnet, and a switch controlled by the armature.
15. In an automobile horn, the combination of supporting means, a diaphragm associated therewith, an electromagnet having a square faced core, an armature adapted when attracted by the magnet to move in a

path substantially parallel to the face of the magnet core to actuate the diaphragm and means for connecting the armature to the supporting means restraining said armature to move in a path which clears the magnet.

16. In an automobile horn, the combination of supporting means, a diaphragm, an electromagnet mounted with its operating end adjacent the central portion of the diaphragm, and an armature adapted when attracted by the magnet to move in a path substantially parallel to the face of the end of the magnet core to actuate said diaphragm and means to restrain said armature to movement in such path.

17. In an automobile horn, the combination of a flat frame piece having a large opening in the center thereof, a diaphragm associated with the frame-piece and means to connect the diaphragm to the front of the frame-piece, electromagnetic means comprising a winding and a plurality of core limbs, means to mount said magnet means through 25 ends of said limbs to the backside of the frame-piece, with said limbs extending part way across the opening in the frame-piece substantially parallel to the diaphragm and with the operating end of the limbs adjacent 30 the central portion of the diaphragm, said electromagnetic means being supported in the opening in the frame-piece with a portion of said means below the rear surface of the frame, an armature for said means, and 35 means including a flat leaf spring for supporting said armature from the frame-piece, one end of said spring being connected to the armature and the other end connected to the backside of the frame-piece, said supporting means normally holding the armature to one side of the electromagnetic means and over the central portion of the diaphragm with the armature normally disconnected from the diaphragm, said armature 40 when operated by the electromagnetic means swinging to one side of said electromagnetic means in a path which clears the electromagnetic means and in a direction substantially perpendicular to the long axis thereof, 45 and a pair of contacts constituting an electric switch controlled by said armature.

18. In an automobile horn, the combination of a flat frame-piece with a large opening in the central portion thereof, said 55 frame-piece consisting of a ring of metal, a vibratory diaphragm of substantially the same diameter as the frame-piece, a casing front, means for connecting the front, the diaphragm and frame-piece together with 60 the diaphragm between the front and frame-piece, a resonator associated with the opening in the casing front, electromagnetic means comprising a plurality of core limbs and a magnet winding associated with said 65 core, means to connect the core limbs to the

backside of the frame-piece with the limbs extending over the opening in the frame-piece and parallel to the diaphragm, with the free ends of the limbs adjacent the central portion of the diaphragm, an armature for 70 said electromagnetic means, a flat spring for connecting the armature to the frame-piece, means to connect one end of the spring to the armature, means to connect the other end of the spring to the back of the frame-piece, said armature being supported to one side of the electromagnetic means, over the central portion of the diaphragm and out of alignment with the electromagnetic means with respect to the diaphragm, said armature when operated by the magnet means swinging to one side thereof and in a path which clears the magnet means and in a direction substantially perpendicular to the long axis thereof, and a pair of contacts constituting an electric switch controlling the current flow through the winding of the electromagnetic means governed by said armature.

19. In an automobile horn, the combination of a flat frame-piece having a large opening in the central portion thereof, a diaphragm of substantially the same diameter as the frame-piece extending over the opening in the frame-piece, a front piece, 90 means to connect the diaphragm, the front piece and the frame-piece together, with the diaphragm between the frame-piece and the front piece, said connecting means being applied to the edge of the diaphragm leaving the central portion thereof free to vibrate, an electromagnet comprising a core and a winding, means to connect one end of the core to the backside of the frame-piece with said magnet extending over the 95 opening in the frame-piece substantially parallel to the diaphragm, and with its operating end adjacent the central portion of the diaphragm, a portion of said electromagnet being within the opening in the 100 frame-piece and below the back surface thereof, an armature for operating the diaphragm, a leaf spring for connecting the armature to the frame-piece, means connecting one end of the leaf spring to the armature and means connecting the other end of the leaf spring to the backside of the frame-piece, said armature and spring being substantially parallel to the diaphragm, said supporting means normally holding the armature to one side of the electromagnet and over the central portion of the diaphragm, said armature when operated by said electromagnet swinging to one side of said electromagnet in a path which clears the magnet, and in a direction substantially perpendicular to the long axis of the magnet, a projection carried by said armature normally disengaged from the diaphragm, but adapted to strike the diaphragm when the 110 115 120 125 130

armature is vibrated, and a pair of contacts constituting an electric switch connected to the backside of the frame-piece, said switch controlling said electromagnet and governed by said armature.

20. In an automobile horn, the combination of a flat circular frame-piece having a large opening in the central portion thereof, a vibratory diaphragm of substantially the same diameter as the frame piece, a front piece, means to clamp the front piece, the frame piece and the diaphragm together with the diaphragm between the frame piece and the front piece, the edges of the diaphragm being fastened to the other members and the central portion being free to vibrate, electromagnetic means comprising a plurality of core limbs and a magnet winding, the limbs being connected upon the backside of the frame-piece and normally held in position where each is equidistant from the diaphragm and parallel thereto, said limbs extending over the opening in the frame piece with their operating ends adjacent the central portion of the diaphragm, said electromagnetic means being thus supported in the opening in the frame-piece with a portion thereof below the rear surface of the frame-piece, an armature for said means, a flat leaf spring connected at

one end to said armature and at the other end to the back of the frame-piece, said armature and leaf spring being normally substantially parallel to the diaphragm, said armature being held by said leaf spring and the connecting means to the side of the free ends of said core limbs and over the central portion of the diaphragm, said armature when operated by the electromagnetic means swinging to one side of the ends of said limbs in a path which clears the electromagnetic means and in a direction substantially perpendicular to the long axis of said electromagnetic means, an electric switch comprising a pair of contacts and means to connect said contacts to the backside of the frame-piece, said switch controlling said winding and operated by said armature and a projection carried by the armature, normally disengaging the diaphragm but adapted to strike and operate the same when the armature is vibrated.

In witness whereof I have signed my name in the presence of two witnesses this 2nd day of May, 1914.

RAY H. MANSON.
